APPARATUS FOR NESTING FLAT DRINKING CUPS

Shala W. Henry, Hyde Park, Mass., assignor to Edgar McCallum, Falmouth, Mass.

Application August 19, 1939, Serial No. 290,961

10 Claims. (Cl. 93—36.05)

This invention relates to an apparatus for loading flat open-mouthed paper drinking cups into a magazine in nested relation thereby to form a stack of nested cups.

5 Flat paper drinking cups are commonly made by folding a blank of paper into cup shape with the edge portions of the blank having an overlapping relation and adhesively secured together. In these cups, the adhesively united overlapping edges of the blank are usually located on one side of the flat cup, thereby producing two plies or thicknesses of paper on said side. The other side of the cup, however, is formed from a single ply or thickness. For convenience in describing 10 the invention, I will refer to the single ply side of the cup as the "front side" and the other side having the two plies or thicknesses as the "back side," it being understood that these terms are used arbitrarily and merely for convenience in identifying the opposite sides of the cup.

Drinking cups of this type are usually used in connection with a cup dispenser adapted to receive a stack of nested cups and arranged to deliver the cups singly from the stack as needed. 15 If a stack of nested cups is formed with the single ply front side of all the cups on the one side of the stack and the two-ply back side of all the cups on the other side of the stack, there will be a tendency for the stack to assume a curved shape, rather than extending in a straight line, thereby making it more difficult to handle the stack of nested cups when they are being packaged or being introduced into a cup-dispensing apparatus.

20 One of the objects of the present invention is to provide an apparatus for nesting drinking cups in such a manner that part of the cups in the stack of nested cups will have their single ply sides on one side of the stack and the other cups will have their single ply sides on the other side of the stack. In the preferred embodiment of the invention which is herein illustrated, the apparatus is constructed so that the alternate cups are placed in the stack in nested relation with the single ply front side on one side of the stack and the other cups are arranged with 25 their single ply front side on the opposite side of the stack. With this arrangement, any two adjacent nested cups in the stack are reversed in position relative to each other, one of such cups having its front side on one side of the stack and the other having its front side on the opposite side of the stack. By so doing, a stack of paper drinking cups can be built up which will 30 have no tendency to curve one way or the other.

but will maintain its desired straight-line condition.

The device herein illustrated is provided with a platform onto which the drinking cups are delivered, one by one, a magazine adapted to hold 5 a stack of nested cups, and a cup-transferring member adapted to take the cups from the platform one by one and deliver each cup to the magazine in nested relation to the stack of nested cups therein.

10 Another object of my invention is to provide novel pneumatic means for holding each cup in position on the platform while the cup transferring member is being manipulated into position to take the cup from the platform and 15 also to hold the cup on the cup transferring member while the cup is being transported thereby from the platform to the magazine.

Further objects of the invention are to provide an apparatus of this type in which the cup transferring member is manipulated so as to place the cups in nested relation in the magazine with the single ply sides of the alternate cups on one side of the stack and the single ply side of the remaining cups on the opposite side 20 of the stack.

25 Further objects of the invention are to improve devices of this type in various particulars which will be more fully hereinafter set forth.

Referring now to the drawings wherein I have 30 illustrated a selected embodiment of the invention:

Fig. 1 is a view partly in section showing a device for nesting the cups in accordance with this invention;

Fig. 2 is an enlarged section on the line 2—2, 35 Fig. 1;

Fig. 3 is a face view of the valve element 66;

Fig. 4 is a view of the element 59 of the valve mechanism;

Fig. 5 is a face view of the valve element 68;

Fig. 6 is an enlarged section on the line 6—6, 40 Fig. 1;

Fig. 7 is an enlarged plan view of the cup transferring member and means for operating it;

Fig. 8 is a fragmentary view of the guide tube 45 for the cup transferring member;

Fig. 9 is a section on the line 9—9, Fig. 7;

Fig. 10 is a fragmentary view showing the cup transferring member in side elevation and illustrating the operation of placing a cup into the magazine;

Fig. 11 is a section through the magazine on the line 11—11, Fig. 12;

Fig. 12 is a section through the magazine on 55

the line 12—12, Fig. 11, said Fig. 12 showing a stack of nested cups in the magazine;

Fig. 13 illustrates the type of flat paper cup which this machine is adapted to load into a magazine in nested relation;

Fig. 14 shows a stack of cups which have been nested in accordance with this invention;

Fig. 15 is a fragmentary sectional view of the cup transferring member showing the manner 10 in which any cup is retained thereon by pneumatic means.

Referring first to Fig. 13, 1 indicates a flat open-mouthed paper drinking cup of the type which is very commonly used. This cup is made 15 from a blank of paper which is folded into cup shape with the marginal portions 2 and 3 of the blank having an overlapping relation and being adhesively secured together. The bottom of the cup is folded over as shown at 4 thereby to provide a closed bottom, and this folded overlapping portion 4 is also adhesively secured to the side wall of the cup. A cup having this construction presents two folded edges 5 and 6, and one side 7 of the cup, which for convenience will be referred to as the "front side," is formed from a single ply or thickness of the paper, while the other side 8, which for convenience will be referred to as the "back side," has the two thicknesses or plies where the portions 2 and 3 of the blank overlap each other.

My present invention provides means for assembling open-mouthed flat drinking cups 1 such as shown in Fig. 13 in nested relation but with the single ply front side 7 of the alternate cups 35 in the stack of nested cups on one side of the stack and the single ply front side of the remaining cups on the opposite side of the stack, as shown in Fig. 14, wherein the bottom cup 1a of the stack has its back side 8 toward the observer, while the second cup 1b of the stack has its front face 7 toward the observer, and the third cup 1c also has its back side 8 toward the observer, while the fourth cup 1d has its front side 7 toward the observer, and so on. With this arrangement, the alternate cups in the stack have their back sides on one side of the stack and the remaining cups in the stack have their front sides on said side of the stack. The double thickness or two-ply side of half the cups in the stack will thus be on one side of the stack and the two-ply or double thickness back side of the remaining cups in the stack will be on the other side thereof.

The device for thus stacking the cups comprises 55 a platform 9 (see Fig. 1) onto which the cups 1 are delivered one by one, a magazine 10 adapted to receive a stack 12 of nested cups, such as shown in Fig. 14, and a cup transferring member 11 adapted to take the cups 1 singly from the platform 9 and deliver them to the magazine in nested relation to the stack 12 of cups therein.

These operative parts of the apparatus are supported on a suitable frame 13.

The cups may be formed from the blanks by any known mechanism and delivered onto the platform 9 by any suitable means. Inasmuch as the invention is not concerned with the means for making the cups, I have not illustrated any such cup-making means herein, it being sufficient to state that the cups after being properly folded and formed, are delivered one by one onto the platform 9. There is shown herein a pair of guide rolls 14 which are suitably supported by the frame 13 and to which the individual cups 75 are delivered from the cup-making device, said

cups passing between the rolls 14 and through the chute 15 to the platform 9.

The magazine 10 is shown as having a trough-shape, it being open at the top, and as having at one end a plate 16 provided with an opening 17 through which the individual cups are delivered into nesting relation with the stack 12 of cups in the magazine. This magazine is suitably carried by a bracket arm 18 which is mounted on the frame 13.

The individual cups are delivered to the platform 9 with the bottom end of the cup directed toward the magazine and with the open top end of the cup directed away from the magazine. Said cups, when delivered to the platform 9, 15 assume a horizontal position thereon.

The cup transferring member 11 is provided with a flat head 18 adapted to be introduced into the open end of the cup, and means are provided for manipulating the head 18 so as to move it forwardly from its retracted position shown in Figs. 1 and 9 into the open mouth of the cup, and then to continue the forward motion of the head during which the cup is transported thereby from the platform 9 into the magazine 10 through the opening 17 in the plate 16. Means are provided for giving the head 18 and the magazine a relative turning movement during each forward movement of the head so that the successive cups are deposited into the stack 30 of cups in reversed position. In the illustrated embodiment of the invention, this relative turning movement is secured by giving the head 18 a rotative movement, said head being given a quarter turn during each forward movement, 35 thereby turning the cup from its horizontal position on the platform into a vertical position corresponding to the position of the aperture.

After each cup has been deposited in the magazine, the cup transferring member is given a 40 backward movement to its initial position, and during such backward movement, it is again given a quarter turn so that it has a horizontal position ready to pick up the next cup.

Means are provided to prevent each cup from being withdrawn from the magazine when the cup transferring member is given its backward movement, and for this purpose I have provided two spring arms 19 which are carried by the back side of the plate 16 and which are situated to be engaged by the corners 20 of each cup as it passes through the opening 17. These spring arms are pressed aside as each cup is delivered through the aperture 17 and then they spring back into position 55 to hold the cup from being withdrawn from the stack when the head 18 is withdrawn, as clearly seen in Fig. 12.

The head 18 is mounted on a rod 21 which is supported by a guide sleeve 22, the latter being mounted at one end in a supporting bracket 23, and at the other end in a portion 24 of the frame on which the platform 9 is mounted. The rod 21 with its head 18 is given its reciprocating movement by means of a cam 25 carried by a cam shaft 26. This cam acts on a follower 27 carried by a lever 28 which is pivotally mounted to the frame at 29, said follower being held in engagement with the cam by the spring 32 which is attached to the lever 28. The upper end of the lever is connected by a link 30 to a sleeve-like head 31 which encircles and is slidably mounted on the guiding sleeve 22. The sleeve-like head 31 is connected to the stem 21 of the cup transferring member so that the cam actu- 75

ated movement of the lever 28 will give reciprocating movement to the cup transferring member.

As herein shown, the stem 21 has fast thereon a collar 34 which is situated within the guiding sleeve 22 and said collar has a pin 35 extending outwardly therefrom which operates in a slot 36 formed in the guiding sleeve 22 and extends through the head-like sleeve 31. Thus, when the head 18 is moved back and forth by the lever 28, such back and forth movement will be transmitted to the stem 21 and head 18 through the pin 35 and collar 34.

Means are provided for giving the head 18 a quarter turn during each forward movement, thereby to turn each cup from the horizontal position which it has on the platform 9 into the vertical position necessary to insert it through the opening 17 of the magazine, and such means is constructed so that during successive forward movements of the head, it will be turned in opposite directions. By this means, the successive cups are placed in the stack in reversed position.

The slot 36 of the guiding sleeve 22 is provided with two branches 36a and 36b, one on one side 25 of the sleeve 22 and the other on the opposite side.

As the cup-transferring member is moved forward from its retracted position, the pin 35 travels in the slot 36, and means are provided whereby 30 during every alternate forward movement, the pin will be directed into the branch 36a, and during the other forward movements, it will be directed into the branch 36b. The movement of the pin 35 into either branch 36a or 36b of the groove 35 serves to turn the stem 21 about its axis, thereby turning the head 18 from the horizontal position shown in Figs. 1 and 7 into the vertical position shown in Fig. 10.

The movement of the pin into either one or the other of the branch grooves 36a, 36b is controlled by a switch cam 37 which is pivotally mounted on the frame at 38.

This switch cam has a pointed end 39 which is adapted to close one or the other of the branch grooves 36a, 36b, according to the position of said switch. When the switch is in the full line position, Fig. 7, the pointed end overlies and closes the branch groove 36b so that when the stem 21 and head 18 move forwardly, the pin 35 will be diverted by said switch cam into the branch 36a, and thus the head 18 will be given a quarter turn into a vertical position with the left hand end of said head as shown in Fig. 7 on the upper side and the right hand end of the head on the under side.

If the switch cam is swung into the dotted line position, Fig. 7, then the point thereof will close the branch groove 36a so that on the forward movement of the head 18 and stem 21, the pin 35 will be diverted into the branch 36b, which will result in giving the head a quarter turn but in a direction which will bring the right hand end of the head 18 in Fig. 7 to the top on the left hand end, as shown in Fig. 7 on the under side. The movement of the switch cam 37 is controlled by a cam member 40 which is mounted on a stud 41 journaled in the portion 24 of the frame. This cam 40 cooperates with a follower 42 carried by the extension 43 of the switch cam 37 and the latter is acted on by a spring 44 which holds the follower in engagement with the cam 40. The cam surface of the cam 40 is on the side face thereof and said cam surface presents the high portion 45 and the low portion 46. When the follower is on the high portion 45 as shown in

Fig. 7, the switch cam is in a position to close the branch groove 36b, but when the cam has rotated so that the follower is running on the low portion of the cam, then the spring 44 will swing the switch cam into the dotted line position, thereby closing the branch groove 36a. 5

This cam 40 is rotated in timed relation with the rotation of the cam 25, said cam 40 rotating once for every two rotations of the cam 25, so that during each alternate forward movement of the cup transferring member, the switch cam will be in the full line position, Fig. 7, while during the other forward movements of said member, the switch cam will be in the dotted line position, Fig. 7. 10

While any suitable means for rotating the cam 40 may be employed, I have herein shown said cam as having a sprocket wheel 47 rigid therewith which is actuated by a sprocket chain 48 driven from a sprocket wheel 49 on a shaft 50. 20 This shaft 50 will be operated in suitable timed relation with the shaft 26 so that the rotation of the cam 40 will be timed properly relative to the reciprocating movement of the cup transferring member. 25

The device herein illustrated also comprises means for holding each cup 1 to the platform 9 by suction while the head 18 of the cup transferring member is moving forwardly into the open mouth of the cup, and then to hold the cup to 30 said head 18 by suction while the cup is being transported from the platform into the magazine, the suction being cut off as soon as the cup has been nested into the stack and before the cup transferring members is retracted. The platform 35 9 is provided with a suction port 51 which is situated in that part of the platform on which the top portion of the cup rests after it has been delivered to the platform, and this suction port communicates with a pipe 52 which extends to 40 a valve device 53 that controls the application of suction to said port 51. The suction is produced by any suitable suction fan or exhaust mechanism which is connected to the valve 53 through a suction pipe 54, and the valve operates 45 to automatically establish communication between the pipe 52 and the suction pipe 54, just after a cup has been delivered onto the platform, and to cut off said suction as soon as the head 18 has entered the cup preparatory to transporting 50 it to the magazine 10. The suction at the port 51 draws the under side of the cup down firmly against the platform, thus holding the mouth of the cup open so that the head 18 may freely enter the same. 55

The head 18 is provided with two suction ports 55, 56, one on each side thereof, and said ports communicate with a passage way 57 extending axially of the stem, said passageway leading to 60 and communicating with a flexible pipe 58 which is connected to the end of the stem. This pipe 58 also leads to the valve 53 and the latter is constructed so that as soon as the head 18 has entered the open mouth of a cup and the suction at the port 51 is cut off, the pipe 58 will be connected with the suction pipe 54, thus producing suction at the ports 55, 56 which will draw the opposite sides of the cup down against the head 18 as shown in Fig. 15, thus securely holding the cup on the head. This suction is maintained at 65 the ports 55, 56, during the forward movement of the head and until the cup carried by the head has been deposited into the magazine 10 in nested relation with the stack of cups therein. The valve 53 then closes the communication be- 70 75

tween the suction pipe 54 and the pipe 58, thus breaking the suction at the ports 55, 56, so that the retraction of the head will not withdraw the cup from the magazine.

5. A suitable valve device adapted to function in this way is shown in Figs. 2 to 5. This valve comprises a rotary valve member 59 which is shown as rotatably mounted on a stud 60 carried by a bracket arm 61 rising from the frame. The rotary valve 59 is provided with a port 62 which extends through the latter. This valve member is shown as provided with a hub 63 on which is made fast a sprocket wheel 64 by which the valve member is turned, and said sprocket wheel 15 is shown as being driven by a sprocket chain 65 leading to a sprocket wheel on the shaft 50.

66 is a disk which is stationarily mounted on the hub 63, one face of said disk engaging the side face of the valve member 19 and having 20 therein an annular chamber 67 which is in constant communication with the suction pipe 54, the latter being screwed into the edge of the stationary disk 66, as shown in Fig. 2.

68 indicates another stationary disk mounted 25 on the stud 60 and engaging the other face of the valve member 59. This disk 68 is also a stationary disk and may be held in place on the stud 60 by suitable set screw 69. The disk 68 is provided with a small chamber 70 in the face thereof 30 which engages the valve member 59, said chamber 70 having constant communication with the pipe 52. The disk 68 is also provided with an elongated chamber 71 in the face thereof which contacts with the rotary valve 59, said chamber 71 having constant communication with the pipe 58.

The port 62 of the valve member 59 is in continuous communication with the annular chamber 17 and thus in continuous communication 40 with the suction pipe 54.

As the valve member 59 rotates, the port 62 is brought into register, first with the chamber 70 of the disk 68, and then with the chamber of said disk. When the valve port 62 is registering 45 with the chamber 70, as shown in Fig. 2, said valve will afford a direct communication between the suction port 51 in the platform 9 and the suction pipe 54, whereby a suction will be produced at said port 51. As the valve member 59 rotates, the port 62 therein is moved out of register with the chamber 70, thus breaking the vacuum at the port 51, and into register with the chamber 71, thus bringing the pipe 58 into communication with the suction pipe 54, and establishing suction at the ports 55, 56 of the cup 50 transferring member. The chamber 70 is of sufficient length so that the suction will be maintained at the ports 55, 56, during the movement of the cup transferring member by which the cup is transported from the platform 9 into the magazine, and as soon as the cup has been deposited in the magazine in nesting relation with the stack of cups therein, the valve port 62 will be carried out of register with the chamber 71 60 thereby breaking the suction at the ports 55, 56.

The means for operating the valve member 59 is such as to cause said member to make one rotation for each rotation of the cam 25 so that 70 the valve which controls the suction is operating in timed relation with the movements of the cup transferring member.

I claim:

1. An apparatus for nesting drinking cups comprising a platform, means for delivering drinking

75 cups singly to the platform, a magazine for holding a stack of nested cups, a cup transferring member to take each cup from the platform and deliver it into the magazine in nested relation to the stack of nested cups therein, and means for turning the cup-transferring member alternately in opposite directions as successive cups are delivered.

2. An apparatus for nesting drinking cups comprising a platform, means for delivering completely made drinking cups singly onto the platform, a magazine for holding a stack of nested cups, and a cup transferring means to deliver cups singly from the platform to the magazine in nested relation to the stack of nested cups 15 therein and with adjacent cups in the stack in reversed relation to each other.

3. An apparatus for nesting flat drinking cups which have a front side and a back side, said apparatus comprising a platform onto which cups 20 are delivered singly, a magazine for holding a stack of nested cups, and cup transferring means to deliver cups singly from the platform to said magazine in nested relation to the stack of nested cups therein and with the front sides of alternate cups of the stack facing in one direction and those of the other cups in the stack facing in the opposite direction.

4. An apparatus for nesting flat drinking cups comprising a platform onto which cups are delivered singly, a magazine for holding a stack of nested cups, a reciprocating cup transferring member to take cups singly from the platform and deliver them into the magazine in nested relation to the stack of nested cups therein, and means for giving the cup transferring member a turning movement first in one direction and then in the opposite direction as successive cups are delivered to the magazine.

5. An apparatus for nesting flat drinking cups 40 comprising a platform onto which cups are delivered singly, a magazine for holding a stack of nested cups, a reciprocating cup transferring member to take cups singly from the platform and deliver them into the magazine, and suction means to retain each cup on the platform until it is picked up by the cup transferring member.

6. An apparatus for nesting flat drinking cups comprising a platform onto which cups are delivered singly, and which is provided with a suction port, a magazine for holding a stack of nested cups, a reciprocating cup transferring member to take cups singly from the platform and deliver them into the magazine, means to reciprocate the cup transferring member, and means 50 to apply suction to the suction port in the platform after a cup has been delivered thereto but before the cup is picked up by the cup transferring member.

7. An apparatus for nesting flat drinking cups 60 comprising a platform onto which cups are delivered singly, a magazine for holding a stack of nested cups, a cup transferring member having a head to enter the open end of a cup on the platform and of a size to fit the interior of 65 the cup, means to actuate the cup transferring member thereby to transport a cup from the platform to the magazine, and suction means to retain the cup on said head during the transportation thereof.

8. An apparatus for nesting flat drinking cups comprising a platform onto which cups are delivered singly, a magazine for holding a stack of nested cups, a reciprocating cup transferring member having a head to enter the open end of 70

5 a cup on the platform and of a size to fit the interior of the cup, said head having suction ports, means to reciprocate the head to transport a cup from the platform to the magazine, and means to apply suction to said ports during the transportation of the cup.

9. An apparatus for nesting flat drinking cups comprising a platform onto which cups are delivered singly, a magazine for holding a stack of nested cups, a cup transferring member having a head to enter the open end of a cup on the platform, and also having a stem, a guiding sleeve through which the stem extends, said sleeve having a slot formed with two branches, a pin rigid with the stem and operating in said slot, means to reciprocate the cup transferring member, and means for directing the pin into the two branches of the slot alternately during successive forward movements of the cup transferring member,

whereby the head is turned first in one direction and then in another during successive movements thereof.

10. An apparatus for nesting flat drinking cups comprising a platform onto which cups are delivered singly, a magazine for holding a stack of nested cups, a cup transferring member having a head to enter the open end of a cup on the platform, and also having a stem, a guiding sleeve through which the stem extends, said sleeve having a slot formed with two branches, a pin rigid with the stem and operating in said slot, means to reciprocate the cup transferring member, and a swinging cam for directing said pin into the two branches of the slot alternately during successive forward movements of the cup transferring member.

10 SHALA W. HENRY.
